(57) **CLAIM**

The ornamental design for an extended wine rack as shown
and described.

DESCRIPTION

FIG. 1 is a front perspective view of a shelf for an extended
wine rack shown isolated on its own for clarity of the
disclosure.

FIG. 2 is a bottom perspective view thereof.

FIG. 3 is a left side elevation view thereof.

FIG. 4 is a right side elevation view thereof.

FIG. 5 is a front elevation view thereof.

FIG. 6 is a top plan view thereof.

FIG. 7 is a bottom plan view thereof.

FIG. 8 is a cross-sectional view of the shelf for the extended
wine rack taken along line 8-8 shown in FIG. 3.

FIG. 9 is a cross-sectional view of the shelf for the extended
wine rack taken along line 9-9 shown in FIG. 6.

FIG. 10 is a cross-sectional view of the shelf for the
extended wine rack taken along line 10-10 shown in FIG. 6.

FIG. 11 is a cross-sectional view of the shelf for the extended
wine rack taken along line 11-11 shown in FIG. 6.

FIG. 12 is a cross-sectional view of the shelf for the
extended wine rack taken along line 12-12 shown in FIG. 6.

FIG. 13 is a frontal perspective view of the extended wine
rack, shown in an assembled configuration.

FIG. 14 is an exploded front perspective view of the
extended wine rack; and,
